UNITED STATES PATENT OFFICE

PEDER B. HOYE, OF MAYWOOD, ILLINOIS, ASSIGNOR TO ELECTRICAL ENGINEERS EQUIPMENT CO., OF MELROSE PARK, ILLINOIS, A CORPORATION OF ILLINOIS

DISCONNECTING SWITCH

Application filed September 2, 1927. Serial No. 217,060.

This invention relates to electric switches, particularly to disconnecting switches and its object is the provision of generally improved, simplified and inexpensive means for breaking the static friction between the parts and readily and positively opening the switch regardless of adverse influences tending to hold it closed.

Where the switch is provided with locking or latch means for preventing the switch accidentally moving from its desired position, such as might result from a heavy flow of current, vibration or insecure contact, the present invention provides for releasing the locking or latch means before or in applying the powerful opening action so that the switch will be free to open thereunder.

The switch opening means of the present invention releases the lock or latch where there is a lock or latch. It imparts a relatively great or powerful force for separating the blade means from its co-operating contact or terminal and thereafter performs the function of an operating lever or member for separating the blade means from the contact and moving same to full open position.

The opening means of the present invention is also operative to close the switch into proper contact with the associated switch contact or terminal.

It is to be understood that the present invention is not limited to a particular switch and that the details of the embodiment of the invention selected for illustration may be varied within the scope of the appended claims.

In the accompanying drawings:

Fig. 1 is a top plan view of a switch embodying the present invention;

Fig. 2 is a side elevational view of the same;

Fig. 3 is a section taken on the line 3—3 of Fig. 4;

Fig. 4 is a section taken on the line 4—4 of Fig. 3 showing the manner of releasing the locking or latch means and the manner of camming the blade means off of the switch contact or clip member;

Fig. 5 is a detailed section taken on the line 5—5 of Fig. 4;

Fig. 6 is a side elevational view of another embodiment of the invention in which there is no locking or latch means;

Fig. 7 is a top plan view of the same; and

Fig. 8 is a detailed section taken on the line 8—8 of Fig. 6.

The switches shown are double blade switches, such as are shown in Getts Patent 1,212,161 of January 9, 1917 and Jacobs Patent 1,515,116 of Nov. 11, 1924.

Referring first to Figures 1 to 5, the movable part of the switch comprises a pair of blades 5 and 6 which are clamped at one end to a stationary hinge or pivot terminal 7 by means of a bolt 8 and a pair of spring washers 10 which maintain a uniform spring pressure upon the blades 5 and 6 to hold them against the opposite sides of the terminal 7. The terminal 7 is suitably mounted upon the end of a supporting insulator 12 and the terminal has a projection 13 to which the desired conductor may be secured and connected as through a socket terminal or the like.

The contact terminal into and out of engagement with which the movable part or blade means 5, 6 is swung by pivotal movement about the pivot bolt 8, is indicated at 15. The contact terminal 15 is suitably mounted upon the outer end of a supporting insulator 16 and is provided with a suitable projection 17 to which the other conductor may be secured and connected therewith. For holding the outer or free ends of the blades 5, 6 against the sides of the outer or contact terminal 15 when the blades are in engagement therewith, a pair of bolts 18 and 19 are employed, one on each side of the terminal 15 and each provided with a pair of spring washers 20.

The locking device shown in connection with Figures 1 to 5 comprises a pair of latch arms 22, one on each side of the movable switch member 5, 6 and yieldingly pressed to locking position for holding the switch closed. These latch arms 22 are provided with shoulders 23 for engaging over the outer edges of the blades 5, 6 to hold the

switch closed. Outwardly of the shoulders 23, the latch arms 22 have outwardly spreading or flared extensions 24.

Extending along the outer side of each 5 latch arm 22 is a guide 26. The guides 26 are disposed on opposite sides of the contact 15 and each is preferably of channel formation, as shown to enclose the latch arms 22 and the means for yieldingly pressing the 10 latch arms to locking position. The inner ends of the guide members 26 have base portions 28 and are flanged at 29 and suitably attached as by means of bolts 30 to the base of the terminal 15 and outer end of the supporting insulator.

The outer ends of the guide members 26 are turned back at 32 and form a throat 33 which normally substantially coincides with the outer end of the terminal 15 and guides 20 the blades 5, 6 in onto the opposite sides of the terminal 15. The base portions 28 of the guide members 26 are recessed at 35 and each latch arm 22 is provided at its inner end with a knuckle 36 pivoted in these recesses 35 on opposite sides of the terminal 15. A pair of coiled springs 38 interposed between the outer side of each latch arm 22 and the inner side of the adjacent guide member 26 yieldingly bias or press the latch 30 members 22 into locking position with the shoulders 23 engaging over the outer edges of the blades 5, 6 when said blades are in closed position. The locking positions of the latch arms 22 are shown in dotted lines 35 in Figure 3 and these arms 22 are swingable about their pivoted knuckles 36 and against the tension of the springs 38 into the positions shown in full lines in Figure 3 for the purpose of releasing the blades 5, 6 for opening movement. The springs 38 may be held in position by sockets 39 on the inner sides of the members 26 and pins or studs 40 on the outer sides of the arms 22.

A lock release and operating lever 45 is 45 pivoted between the outer ends of the blades 5, 6 adjacent the terminal 15 and bolt 18 upon a pivot pin 46 which extends through and is suitably secured at its opposite ends in the blades 5, 6.

50 The inner margin of the operating lever is of a thickness at 48 substantially the same or slightly less than the thickness of the contact lug 15 and this inner margin 48 fits and is swingably operative between the 55 blades 5, 6. The margin 48 of the lever 45 has an angular recess 50 forming the upper portion 50' which overhangs the upper edge of the terminal 15 when the blade means is in the closed position and a depending cam extension 53 rounded at 54 for camming engagement with the outer end of the terminal lug 15. The overhanging extension 50' is angularly recessed at 55 for cooperation with the bolt 18 in closing the 60 switch.

The depending camming portion 53 of the lever 45 has oppositely extending wedges or lateral flanges 58 which in the switch opening movement of the lever 45 are forced between the latch arms 22 and spread these 70 arms apart and the shoulders 23 out of engagement with the outer edges of the blade members 5, 6 to permit the blade members to be swung outwardly into open position therefrom. As the blade members move outwardly from the contact 15 the lateral flanges 58 engage the outer edges of the blade members 5, 6 limiting further counter-clockwise swinging movement of the lever 45 about the pin 46 and relative the blade members 5, 6 so that thereafter the lever 45 is substantially rigid with respect to the blade means in the direction of pull on the lever which thereafter acts or operates as a pulling lever for pulling the blades 5, 6 85 off of the contact 15.

The operating lever 45 has an eye or opening 60 for receiving a suitable hook with which to operate the switch, as well understood in the art. The hook or other operating means is usually provided on the end of a suitable operating pole.

The switch blades 5, 6 may be made relatively thin in order that they may have freedom to adjust themselves to the sides 95 of the terminals and the outer ends of the terminals may be beveled or mitered off slightly, as shown.

In the closed position of the switch, the locking arms 22 are in locking position as 100 shown in dotted lines in Fig. 3 holding blade means locked in the closed position as shown in Fig. 2 and in full lines in Fig. 4. The operating lever 45 is, in the closed position of the switch, in the position shown 105 in full lines in Figs. 2 and 4. When it is desired to open the switch, the operating rod or hook is hooked into the eye 60 and the lever 45 is pulled in a counter-clockwise direction about the pin 46.

110 The initial movement of the operating lever 45 about its pivot 46 in switch opening direction forces the wedge or lateral flange means 58 between the latch members 22, spreading these latch members 22 into the full line positions shown in Fig. 3 and releasing the shoulder 23 from the outer edges of the blade members 5, 6. Continued movement of the lever 45 forces the depending cam portion 53 into camming engagement with the outer end of the terminal 15 and between the blade members 5, 6, so that as the movement of the operating lever 45 continues a powerful camming action is 120 exerted upon the outer end of the terminal 15 for pulling the blade off of the clip or terminal 15. Then as the blade leaves the terminal 15 its outer edges engage the flanges 58 so that thereafter the lever 45 and the blade members operate 125

rigidly or as a unit, the lever 45 operating as a pulling lever for pulling the blades off of the contact 15 and into full open position.

In closing the switch the operating hook 15 or member is engaged in the eye 60 and the operating lever is pushed or moved in a clockwise direction about its pivot 46 until the recessed extension 50 engages the bolt 18 whereupon the lever 45 acts as a push lever for swinging the blade means as a unit therewith into closed position. As the blade means is closed it is guided between the guide members 26 and between the latch arms 22, the shoulders 23 of which take over the outer edges of the blades and lock the same against accidental opening, as under short circuits or the like.

In the embodiment illustrated in Figures 6, 7 and 8 the same principle of pulling the blade members off of the contact clips or terminal is employed but in this case there is no lock for locking the blade means to the terminal and the lock releasing function of the operating member is omitted.

25 In this case the pivot terminal is indicated at 65 while the contact terminal is indicated at 66. The switch is, as before a double blade switch with the blades indicated at 68 and the operating lever 70 has an extension 72 which fits or extends operatively between the blade members 68 and is pivoted therebetween upon a pin 73 which extends between the blade members and is suitably secured at its opposite ends therein.

35 The lever 70, as before, has a depending camming portion 75 rounded at 76 for camming engagement with the outer end of the terminal 66. The lever 70 is also provided with an eye 78 for engagement by an operating hook, as in the previous embodiment or adapted to be pivotally connected through a pin 79 with an operating rod 80 and fitting 81, particularly in gang operated installations.

45 The lever 70 is provided on each of its opposite sides with an angular laterally extending flange or shoulder portion having an upper part or portion 83 and a lower part or flange portion 84.

50 To open the switch the lever 70 is pulled downwardly or in a counter-clockwise direction about its pivot 73, the depending cam portion 75 engaging the outer end of the contact 66 and exerting a powerful camming action to pull the blade off of the contact 66. As the blade members leave the contact 66 and the swing of the operating lever 70 continues the flange portions 84 are engaged with the outer edges of the

55 switch blades 68 and thereafter the operating lever 70 acts as a pulling lever for pulling the blades as a unit therewith off of the contact and outwardly into full open position.

60 To close the switch the lever 70 is pushed

or moved in the opposite direction about its pivot 73 until the shoulder or flange means 83 engages the outer edges of the blade member 68 whereupon the blade members are pushed or moved as a unit with 70 the lever 70 to closed position, through the co-operation of the shoulders 83 with the outer edges of the blades 68 and the accompanying closing movement of the lever 70.

In this case the principle of pulling the 75 blades off of the contact with a powerful camming action is the same as in the preceding embodiment but the lock and lock releasing means are omitted.

In the embodiment of Figs. 1 to 5 the 80 lateral flanges or shoulder means 58 limit the swing of the lever 45 relative the blades 5, 6 in the direction of switch opening movement of the lever 45, whereas the cooperation of the inwardly extending finger 55, 85 with the bolt 18 limits the swing of the lever 45 relative to the blades 5, 6 in the direction of switch closing movement of the lever 45.

In the embodiment of Figs. 6 to 8, the 90 flanges or shoulders 84 limit the swing of the lever 70, relative to the blades, in the direction of switch opening movement of the lever, whereas the flanges or shoulders 83 limit the swing of the lever 70, relative 95 to the blades, in the direction of switch closing movement.

I claim:

1. In an electric switch, the combination of a relatively stationary contact member, 100 a pair of floating blades movable into and out of engagement with said contact member and an operating lever pivoted to said blades and swingable between said blades into camming engagement with said contact member to impart a powerful camming action for separating said blades from said contact member.

2. In an electric switch, the combination of a relatively stationary contact member, 110 a pair of floating blades movable into and out of engagement with said contact member, an operating lever pivoted to said blades and swingable between said blades into camming engagement with said contact member to impart a powerful camming action for separating said blades from said contact member, and abutment means on said lever engagable with said blades to limit the swing of said lever with respect to said 115 blades for moving the blades to open position by the continued movement of said lever.

3. In an electric switch, the combination of a relatively stationary contact member, 125 a pair of floating blades movable into and out of engagement with said contact member, an operating lever pivoted to said blades and including a camming portion swingable between said blades into camming engage- 130

ment with said contact member to impart a powerful camming action for separating said blades from said contact member, abutment means on said lever engagable with said blades to limit the swing of said lever with respect to said blades for moving the blades to open position by the continued movement of said lever and abutment means on said lever and engagable with said blades for limiting the swing of said lever relative to said blades in the opposite direction for closing the blades through said lever.

4. In an electric switch, the combination of a contact member, a movable switch member, latch members between which the switch member is movable and adapted to lock said member in closed position and an operating lever pivoted on said switch member and having means for spreading said latch members to released position and means extending forward of said last means for imparting a powerful camming action to separate said switch member from said contact member.

5. In an electric switch, the combination of a contact member, a switch member movable into and out of engagement with said contact member, latch members between which said switch member is movable and adapted to lock said member in closed position, an operating lever pivoted on the switch member and having a cam portion co-operable with the contact member to cam said switch member therefrom, and means on said operating lever rearward of the cam portion for spreading said latch members to released position.

6. In an electric switch, the combination of a contact member, a switch member movable into and out of engagement with said contact member, latch members between which said switch member is movable and adapted to lock said member in closed position, an operating lever pivoted on the switch member and having a cam portion co-operable with the contact member to cam said switch member therefrom, means on said operating lever for spreading said latch means to released position, said means being located rearwardly of the cam portion, and means for limiting the swing of said lever relative the switch member for moving the switch member through said lever.

7. In an electric switch, the combination of a contact member, a pair of floating blades co-operable therewith, spring means including a bolt for pressing the blades against the sides of the contact, an operating lever pivoted between said blades and swingable relative thereto, abutment means on said operating lever engagable with the edges of the blades to limit swinging movement of the lever relative the blades in one direction and a projecting finger on said lever engagable with said bolt to limit an operating lever pivoted to said blades

swinging movement of the lever relative the blades in the opposite direction.

8. A switch comprising a pair of spaced insulators, a pivot contact mounted on one of the insulators, a second contact mounted on the other insulator, means associated with each of the contacts for establishing an electrical connection thereto, a pair of parallel switch blades pivoted on the pivot contact and adapted to embrace the second contact between them, and an operating lever pivoted to said blades and having a camming portion swingable into engagement with said second contact to impart a powerful camming action for moving said blades from said second contact, said camming portion moving between said blades and remaining in camming engagement with said second contact after the edge of the blades moves free of the edge of the second contact during the opening movement.

9. A switch comprising a pair of spaced insulators, a pivot contact mounted on one of the insulators, a second contact mounted on the other insulator, means associated with each of the contacts for establishing an electrical connection thereto, a pair of parallel switch blades pivoted on the pivot contact and adapted to embrace the second contact between them, an operating lever pivoted to said blades and having a camming portion swingable into engagement with said second contact to impart a powerful camming action for moving said blades from said second contact, said camming portion moving between said blades and remaining in camming engagement with said second contact after the edge of the blades moves free of the edge of the second contact during the opening movement, and abutment means on said lever engageable with said blades to limit the swing of said camming means between the blades for moving the blades to the full open position by continued movement of the lever.

10. A switch comprising a contact, a pair of parallel switch blades adapted to embrace said contact between them and movable into and out of engagement therewith, and an operating lever pivoted to said blades and having a camming portion swingable into engagement with the contact to impart a powerful camming action for moving said blades from said contact, said camming portion being of a lesser thickness than the distance between the two blades and remaining in camming engagement with the contact and between the blades after the edge of the blades moves free of the edge of the contact during the opening movement.

11. A switch comprising a contact, a pair of parallel switch blades adapted to embrace said contact between them and movable into and out of engagement therewith, and an operating lever pivoted to said blades

and having a camming portion swingable into engagement with the contact to impart a powerful camming action for moving said blades from said contact, said camming portion being of a lesser thickness than the distance between the two blades and remaining in camming engagement with the contact and between the blades after the edge of the blades moves free of the edge of the contact during the opening movement, and abutment means on said lever engageable with said blades to limit the swing of the camming means between the blades for moving the blades to the full open position by continued movement of the lever.

12. A switch having a contact member, a locking member having movement toward and away from the contact member, a switch blade operating between said members and in contact therewith, said locking member being yieldingly urged toward the contact for pressing the blade in firm engagement with the contact, and an operating lever pivoted to the blade, said lever having an abutment portion for spreading the locking member to its unlocked position and having an additional curved camming portion for thereafter engaging the contact to exert a powerful camming action for moving the blade from the contact, said camming portion rolling upon the contact after the edge of the blade clears the edge of the contact thereby continuing the camming action.

13. A switch having a contact member, a locking member having movement toward and away from the contact member, a switch blade operating between said members and in contact therewith, said locking member being yieldingly urged toward the contact for pressing the blade in firm engagement with the contact, and an operating lever pivoted to the blade, said lever having an abutment portion for spreading the locking member to its unlocked position and having an additional curved camming portion for thereafter engaging the contact to exert a powerful camming action for moving the blade from the contact, said camming portion rolling upon the contact after the edge of the blade clears the edge of the contact thereby continuing the camming action and said abutment engaging the blade after a predetermined opening movement for moving the blade to the full open position by a continued movement of the operating lever.

14. A switch having a contact member, a locking member having movement toward and away from the contact member, a switch blade operating between said members and in contact therewith, said locking member being yieldingly urged toward the contact for pressing the blade in firm engagement with the contact, an operating lever pivoted to the blade, said lever having an abutment portion for spreading the locking member to

its unlocked position and having an additional curved camming portion for thereafter engaging the contact to exert a powerful camming action for moving the blade from the contact, said camming portion 70 rolling upon the contact after the edge of the blade clears the edge of the contact thereby continuing the camming action, and additional abutment means on the lever for limiting the swing of the lever with respect to the blade upon movement of the lever to the switch closing position.

15. An electric switch having a pair of spaced parallel floating blades, means including a bolt extending through said blades 80 adjacent one end thereof for holding the blades against spreading, an operating lever pivoted to at least one of said blades for operating the blades, and means including a projecting finger on said lever engageable 85 with said bolt to limit the swinging movement of the lever with reference to said blades.

16. An electric switch including a blade having a pair of spaced parallel contact 90 making members, means including a bolt for holding the contact making members against undue spreading, and an operating member pivoted to the blade and including a portion movable into engagement with 95 the bolt for limiting the extent of pivotal movement of the operating member on the blade in at least one direction.

17. An electric switch including a blade having a pair of spaced parallel contact 100 making members, means including a bolt for holding the contact making members against undue spreading, means for locking the blade in the closed position, and an operating and lock releasing member pivoted 105 to the blade and including a portion movable into engagement with the bolt for limiting the extent of pivotal movement of the operating member on the blade in at least one direction.

18. An electric switch including a blade having a pair of spaced parallel contact making members, means including a bolt for holding the contact making members against undue spreading, and an operating 115 member pivoted to the blade and including a portion movable into engagement with the bolt for limiting the extent of pivotal movement of the operating member on the blade in one direction, and additional abutment 120 means movable into engagement with the blade for limiting the extent of pivotal movement of the operating member on the blade in the opposite direction.

19. A switch having a contact member, 125 a switch blade movable into and out of engagement therewith, an operating lever pivoted to the blade, said lever having a camming portion for engaging the contact to exert a powerful camming action for mov- 130

ing the blade from the contact, said camming portion remaining in camming engagement with the contact after the edge of the blade clears the edge of the contact, thereby continuing the camming action.

5. 20. A switch having a contact member, a switch blade movable into and out of engagement therewith, an operating lever pivoted to the blade, said lever having a curved camming portion for engaging the contact to exert a powerful camming action for moving the blade from the contact, said camming portion rolling upon the contact after the edge of the blade clears the edge of the contact thereby continuing the camming action.

10. 21. A switch having a contact member, a switch blade movable into and out of engagement therewith, an operating lever pivoted to the blade, said lever having a curved camming portion for engaging the contact to exert a powerful camming action for moving the blade from the contact, said camming portion rolling upon the contact after 15 the edge of the blade clears the edge of the contact thereby continuing the camming action, and abutment means thereafter effective for moving the blade to the full open position by a continued movement of the 20 operating lever.

25. In witness whereof, I hereunto subscribe my name this 16th day of August, 1927.

PEDER B. HOYE.
